[57] **ABSTRACT**

A cutting instrument comprising two blades having a common pivot point. The blades have a cutting portion and an actuating portion on opposite sides of the pivot point. A handle is provided for each blade. Means are provided on the actuating portion of each blade to lock the blade into a recess in the handle. The locking means have barbs which coact with the handle to overcome the tendency of the force applied when using the instrument to separate the blade portion from the handle.

FIG. 1

FRANCIS S. DUPREY
INVENTOR.

BY

Marvin S. Blodgett

HANDLE LOCK FOR A CUTTING INSTRUMENT**BACKGROUND OF THE INVENTION**

This application relates to an improved means for locking the blade of a cutting instrument to its corresponding handle. Handles have been provided on cutting instruments for ease of operation and because by making the handle of a material of less density than metal, the total weight of the instrument is reduced. It has been known to secure handles to the blades of cutting instruments by use of a ferrule. The blades are fitted into a recess in the handle and the metal ferrule is driven over the handle, compressing it into contact with the blade. Because great force is repetitively applied in severing material with the cutting instrument, there has been a tendency of the ferrule to loosen and the handle to separate from the blade. When adhesives have been used to secure the handle to the blade in cutting instruments, the repeated flexing during operation has caused the bond to weaken and the components to separate.

SUMMARY OF THE INVENTION

It is an object of the present invention to provide a shear device comprising a pair of metallic blades pivoted together at a common point and actuated by a pair of handles. Each blade has an actuating portion. At the extremity of this actuating portion there is located a positive block means which engages the corresponding handle to lock the two units together in such a manner that the repeated use and flexing resulting therefrom will not weaken the connection between the blade and the handle.

It is a further object of this invention to provide a simple locking device to lock a blade tool to a handle in such a manner that assembly thereof may be readily accomplished.

These and other objects are accomplished by affixing at the end of the actuating portion of the blade means a barbed locking device. This locking device comprises a substantially U-shaped flat element having a plurality of barbs on each side thereof. These barbs are directed outwardly and upwardly in such a manner as to lock into position the actuating portion of the blade means when inserted into a recess in the handle. In the shape of the locking means they are resilient in nature and thereby can be readily compressed during insertion into the recess in the handle. After insertion the barbs, again due to their resilient nature, positively engage the wall surface of the recess in the handle thereby resisting outward movement thereof.

BRIEF DESCRIPTION OF THE DRAWINGS

Other objects and features of the invention will become more apparent by reference to the accompanying drawings, of which:

5 FIG. 1 is a top view of the shear mechanism employing the locking device of the present invention,

FIG. 2 is a side view of the device of FIG. 1, and

FIG. 3 is a detailed view of the locking device of the present invention.

10 DESCRIPTION OF THE PREFERRED EMBODIMENTS

Referring to the drawings, a shear mechanism is shown in which a pair of blades 1,2 connected at a central pivot point 3 have actuating portions 4,5 which, in turn, are operated by handles 6,7, respectively. There is appended to the terminal portion of each actuating portion of the blade means a locking device 8. This locking device 8 is a substantially U-shaped flat metallic element having a plurality of barbs 9 on each side thereof. The locking device 8 is attached to the actuating portions 4,5 of the blade means by riveting, pinning or the like. The barbs 9 are directed outwardly and upwardly in such a manner that during operation they lock the actuating portions 4,5 of the blade means into position in the recesses 10,11 in the handle.

It will be obvious to those skilled in the art that changes and modifications may be made without departing from this invention in its broadest aspects and, therefore, the aim of the appended claims is to cover all such changes and modifications as in the true spirit and scope of this invention.

I claim:

1. In a cutting instrument,
  - a. first and second cutting blades having a cutting portion on opposed portions connected at a common pivot point, and each having an actuating portion,
  - b. a handle for each blade having a concavity into which the actuating portion of its blade can be inserted,
  - c. a protuberance extending from a surface of the actuating portion, in a direction perpendicular to a line between the pivot point and a point on the actuating portion farthest from the pivot point, and
  - d. a locking means, consisting of a substantially U-shaped flat plate having a plurality of barbs extending from the legs of the U-shaped plate in a direction outwardly and toward the open end of the U-shaped plate, the U-shaped plate overlying said surface and being fixed to the protuberance at the elbow in the U-shaped plate.
